UNITED STATES PATENT OFFICE.

EDWARD M. MIKKELSEN, OF CHICAGO, ILLINOIS.

TOWEL-CABINET.

1,156,917.

Specification of Letters Patent. Patented Oct. 19, 1915.

Application filed May 12, 1911. Serial No. 626,661.

To all whom it may concern:

Be it known that I, EDWARD M. MIKKELSEN, a citizen of the United States, residing at Chicago, county of Cook, State of Illinois, have invented a certain new and useful Improvement in Towel-Cabinets, and declare the following to be a full, clear, and exact description of the same, such as will enable others skilled in the art to which it 5 pertains to make and use the same, reference being had to the accompanying drawings, which form a part of this specification.

A piece of furniture found in almost every office is a cabinet for holding towels, 15 a brush and comb and perhaps other toilet articles. Towels are usually supplied once a week in sufficient quantities to last throughout the entire week, the fresh towels being placed in the cabinet by the distributor. The clean towels are therefore taken care of in such a way that their presence is not objectionable. It is common in cabinets of this kind to provide two compartments, one for the clean towels and one for the 20 soiled towels so that if the user places the soiled towels in the proper compartment they will be concealed when the door of the cabinet is closed. There is an objection to 25 all of the cabinets of which I am aware in that the soiled towels, if placed in their proper compartment in the damp condition which necessarily follows from the use of the same become more or less sour and even 30 moldy so that the cabinet soon has a disagreeable odor.

The object of my invention is to produce a cabinet in which there will be ample room for soiled towels, in which the soiled towels will be effectually concealed when the door 35 of the cabinet is closed and in which sourness or mold is prevented.

A further object of my invention is to produce a cabinet having a ventilated chamber for soiled towels, so arranged that the 40 towels may be easily inserted and removed.

The various features of novelty whereby my invention is characterized will hereinafter be pointed out with particularity in the claim; but, for a full understanding of 45 my invention and of its objects and advantages, reference may be had to the following detailed description taken in connection with the accompanying drawing, wherein:

Figure 1 is a perspective view of a cabinet 50 arranged in accordance with a preferred form of my invention, the door of the cabinet

being partially open; Fig. 2 is a plan view of the cabinet with the door closed; and Fig. 3 is a central vertical section through the upper portion of the cabinet at right angles 55 to the rear wall.

Referring to the drawing, 1 represents the cabinet as a whole having the usual mirrored door 2 at the front, and having its interior divided in any suitable way for the 60 reception of the articles which it is desired to keep in the cabinet. In accordance with my invention, I form in the top of the cabinet a compartment 3 large enough to contain all of the soiled towels which accumulate 65 between successive collections. I form an opening 4 in the top of the compartment into which the soiled towels may be inserted and through which they may be removed. It will be seen that if the towels are properly deposited in the compartment so as not to project out of the hole in the top, they 70 will be entirely concealed. Furthermore, even when the door of the cabinet is closed, the soiled towel compartment is open to the 75 surrounding atmosphere and therefore the evaporating moisture in the towels is free to pass up out of the cabinet, thus preventing moisture from collecting in the interior and producing sourness and mold not only in the 80 towels but also in the cabinet. When it is desired to remove the soiled towels it is only necessary to reach in at the top and lift them out of the opening through which they 85 were introduced.

If it is desired to make access to the soiled towel compartment somewhat easier, so as to make it unnecessary to reach above the cabinet when soiled towels are to be deposited the front wall 5 of the soiled towel 90 compartment may be provided with an opening 6 which registers with the opening 4 in the top of the compartment. When the door is closed the opening 6 is covered up thereby and therefore the cabinet presents 95 the same appearance with the door closed as is the case where the opening in the front of the soiled towel compartment is omitted. However, it is somewhat easier to introduce the soiled towels into compartment and remove them therefrom where the opening is formed partially in the top wall and partially in the front wall of the compartment.

While I have illustrated and described only a single preferred form of my invention, I do not desire to be limited to the particular structural details thus illustrated.

and described; but intend to cover all forms and arrangements which fall within the terms employed in the definitions of my invention constituting the appended claim.

5 I claim:

A towel cabinet having a soiled-towel compartment in the uppermost portion thereof comprising two sides, a back connected to the rear portions of the sides, a bottom extending from the back toward the plane of the front edges of the sides and connected to the sides, a front part connected to the front edge of the bottom and also to the sides and extending vertically behind said plane, the upper edge of said front part having a recess therein, a top part connected to said back and said sides

and having its front edge connected to the upper edge of said front part, said front edge having a recess therein corresponding to the recess in the upper edge of said front part, said two recesses together forming an aperture in the angle formed by said front and top parts, and a door hingedly connected to a part of the cabinet and normally 25 extending across the recess in said front part and to the plane of said top part.

In testimony whereof, I sign this specification in the presence of two witnesses.

EDWARD M. MIKKELSEN.
